UNITED STATES PATENT OFFICE.

ANKER S. LYHNE, OF BRIDGEPORT, CONNECTICUT.

FLASH LIGHT.

1,408,527.

Specification of Letters Patent.

Patented Mar. 7, 1922.

Application filed October 18, 1920. Serial No. 417,753.

To all whom it may concern:

Be it known that I, ANKER S. LYHNE, a citizen of the United States, residing at Bridgeport, county of Fairfield, State of Connecticut, have invented an Improvement in Flash Lights, of which the following is a specification.

This invention relates to a pocket flashlight of medium size having features which 10 are not present in the well known forms now in use and which are not suggested in their construction or use.

Of the many objects of the invention, one is to provide a flashlight which when laid 15 on a surface such as a table, is prevented from rolling by reason of the blocking effect of the angular end acting by itself or in conjunction with a clip on the casing. As the flashlight when laid down directs 20 the light at a combined horizontal and vertical angle to the axis of the casing there is no occasion to shift the axis of the casing or raise one end to direct the light as desired.

Another object gained is that this invention 25 makes it possible to hang the flashlight on the clothing for writing, reading music and similar activities when it is desired to have both hands engaged. Likewise this invention can be hung on a hook or on a 30 projection on an automobile during repair operations.

Still a further object is to provide a light which when carried in the hand directs its 35 light to the ground without arching the wrist in order to cover the ground, and maintaining an unnatural position. Similarly in looking at a gas meter or into a gasoline tank the hand and wrist are not 40 interposed in the line of vision or turned to one side to cast the light where desired.

When stood on end it directs its light 45 horizontally instead of upwardly and at all times and places can be refilled with new batteries commonly carried in stock.

Other advantages will become apparent 50 in connection with the following description of the accompanying drawing forming a part of this specification, in which:

Fig. 1 is a perspective view of my novel 55 flashlight showing all exterior features;

Fig. 2, a cross section on the axis; and

Fig. 3 is a perspective view of two portions 60 of the casing showing the connecting joint between the elbow piece and the main casing.

The main casing 10 is of usual form, and

contains one or more dry cells, it being closed at one end where an insulating disc 11 is retained within a flared portion which serves to give an enlarged base upon which 60 to stand the flashlight. Insulation 11 has a turned up rim 12 which encloses a perforate insulation disc 13, both pieces of insulation being retained in intimate relation by reason of the pressure of the adjacent 65 portion of the casing which is of reduced diameter at the edge of insulation 13. A conductor strip 14, placed between discs 11 and 12, is bent at a right angle and is extended along the casing, to the circuit closer 70 15 with retaining button 48, between the strips of insulation 16, 16, which separate the conductor strip from the battery and from the casing 10.

At a point near the center of the base the 75 conductor strip has united to it a short stud 17 extending through the hole in the disc 13 and formed with an enlarged head admitting of adequate electrical connection to one end of a spring 18. The spring, stud, conductor strip and all the insulation members are assembled and inserted in, and forced 80 down so that the rim 12 is pressed upon and retained by the adjacent portion of the casing of reduced diameter. 85

A source of energy capable of causing light in the form of a battery 19, surrounded by insulation 20, all of the usual type, and having a center contact 30 at the lamp end and a corresponding contact upon the surface of the other end is placed in the casing 90 and held so that the spring 18 makes a good contact.

The battery is held against the spring by a cap 21 which telescopes with the casing 95 until its inner edge contacts with a beading 22 formed on the casing 10. In order to retain the parts in position a plurality of circumferentially spaced pins 23 are fastened in the casing at diametrically opposite positions a short way from the bead 22, as shown in Figure 3.

Elongated slots 24 are located in the cap corresponding to the spacing of the pins 23 away from the beading and their width is 100 such as to properly receive the pins. The slots are shaped so as to provide a notch 46 at the end away from the channel 25 and between the notch and the channel there is a wide portion 47 for interrupting the accidental return of the pin 23 to the channel 25. Between the slots and the edge of the cap 110

covered channel 25 is provided so as to admit the pins to the slots and for this purpose the material of the cap between the slots and the edge is pressed outwardly to a height sufficient to pass the pins thereunder.

With this construction it is only necessary to place the cap upon the casing and rotate one or the other until the channel 25 receives the pins, when pressure forces the pins into the slots 24 and a slight pressure and turn moves the pins into the notch 46 of the slot.

A second beading 26 is provided in the cap 21 for positioning an elbow member later to be dealt with in full. The cap carries a disc of insulation 27 which is clamped in position by turning over the outer ends of the cap sufficiently. At the center of disc 27 a hollow rivet 28 is fastened and holds on the exterior the angled lamp contact 29 which is thus in circuit with the battery at the end contact 30.

The lamp 31, of usual form, is screwed into a reflector 32, having a rim 33 held in place against the outer edge of an elbow piece 34 by means of a screw clamping member 35, which has a rim 36, holding the edge of a lens 37 of usual type against the rim 33 and edge of 34.

30 The elbow 34 is formed of solid one piece material of substantially the same thickness as the casing and comprises a cylindrical portion 38, an elbow portion 39, and an enlarged screw portion 40 already referred to. 35 The elbow is sweated to the cap 21 adjacent the bead 26 and thus becomes integral with it.

The elbow portion 39 is pressed into shape so as to form a 90 degree angle to the casing 40 and is merged into the flared portion 40 which carries the screw holding the screw clamping member 35 in place, which holds the lens and the reflector in position. Thus a rigid one piece holding member for the lamp and associated parts is provided which serves to direct the light from the lamp in a direction at an angle to the axis of the casing. The directing of the rays of light as carried out by this flashlight is in no way 45 to be confused with a flexible attachment at this place which must be manipulated by one hand while held in the other. This elbow piece being integral and having an assigned angle needs no manipulation and 50 the direction of its light is controlled by the positioning of the casing which carries it. There is no occasion to limit the angle of the elbow to ninety degrees as another fixed angle may be found more desirable.

55 In addition to the means for directing the light incident to a casing 10 and a fixed flare ended elbow 39, which of themselves will control the direction of the light when the flashlight is laid down along its axis, there 60 is an attaching clip 41 adjustably attached

to the casing and readily removable therefrom. The clip comprises two main portions a circular spring clamp 42 partly encircling the casing 10 between the beads 22 and 26, and a spring clasp 43 with a flanged end 44. A slot 45 having a circular and a straight portion is formed at the upper end of the clip so that the flashlight may be hung upon a nail or the like.

The long spring clasp permits ready insertion behind a belt or the edge of a pocket or other parts of the clothing or in other like places. In addition being slightly arched and extending from the surface of the casing 10, the clip 41 serves as a stop to prevent 70 rolling when the flashlight is laid upon an approximately horizontal surface. At other times when adjusted circumferentially of the casing it cooperates with the flared end 40 of the casing to positively position the casing 75 on the surface.

Again when the clasp 43 is inserted in the belt the casing may be turned in the clamp 42 so that the light is directed in a fixed direction and maintained there.

90 The clamp 42 is made of fairly stiff spring material and shaped to a circle slightly less in diameter than the outer diameter of the casing. It is placed in position by withdrawing the cap 21 and elbow 39 from the casing 10, by unlocking the pin and slot connection described, and forcing the clamp against the bead 26 at which position it may be moved circumferentially of the cap 21 without touching the covering of the channel 25. By 95 reason of its clamping action, due to its reduced diameter, the joint made by the pin and slot connection is reinforced and the parts tightly held and accidental slipping, with consequent falling apart, avoided.

100 As shown in Figure 2, the circuit closer of the usual type is placed on the same side of the casing as the flared screw portion 40 of the elbow 39. By using a plurality of 105 slots and pins as shown in Fig. 3, this position may be varied by circumferential adjustment of the cap and casing and then the circuit closer may be utilized in conjunction with the flared screw portion 40 to control the direction of the light. Likewise the circuit closer and clip 41 may be cooperatively used to control the direction of the light. It is obvious that with the ordinary screw connection, replaced by this joint, the circuit closer would be limited to only one 110 position upon the casing and the above functions would be absent.

115 There are other conjunctive uses of the clip 41 and the circuit closer 15. For instance if the clip is moved around the casing to a point where it lies over the circuit closer retaining button 48 a very tight gripping action will obviously result which is very useful when the flashlight is carried in the pocket of a hard surfaced hunting coat.

With the clip and circuit closer in the same position the clip prevents accidental movement of the circuit closer when the light is carried in a tool box or where articles 5 can move the circuit closer to a position where it permits the battery to run down.

Although this invention has been described in but a single embodiment there has been no intention to limit it in any way as 10 its application to other and various forms was and is contemplated.

Having thus described my invention, I claim:

1. In a flashlight, a casing, a lamp carried thereby, a battery in said casing in connection with said lamp, circuit closing means on the casing, and a casing supporting clip adjustable on the casing to form a spaced guard for said circuit closing means.
2. In a flashlight, a casing, a one piece elbow detachably mounted on one end of said casing, a lamp in said elbow, a casing supporting clip, and means on said clip for preventing dislodgment of said elbow and casing.
3. In a flashlight, a cylindrical casing, a lamp carrying member adapted to be detachably secured on said casing in varied circumferential positions, and a flashlight 30 supporting member disposed on said casing for circumferential rotation thereon, whereby to coact with said lamp carrying member for varying the direction of the light, laterally of the casing.
4. In a flashlight, a cylindrical casing, a

cap, means on said casing and cap for detachably connecting said casing and cap in relatively varied circumferential relation, an elbow on said cap, a lamp support in said elbow, and a casing support member on said 40 cap and circumferentially movable thereon.

5. In a flashlight, a cylindrical casing, a cap, means on said casing and cap for detachably connecting said casing and cap in relatively varied circumferential relation, an 45 elbow on said cap, a lamp support in said elbow, a casing support member on said cap and circumferentially movable thereon, and a clamp on said member for preventing dislodgment of said cap and casing.

6. In a flashlight, a casing, a battery in 50 said casing, a cap detachably secured on one end of said casing, an elbow integral with said cap, a lamp support in said elbow, a lamp in said support, a contact strip carried 55 by said cap and disposed in said elbow in connection with the lamp, a circuit closer on the casing, and a casing supporting clip rotatable on said casing to cover said circuit closer in spaced relation thereto.

7. The combination with a flashlight comprising a casing, a battery therein, a lamp, electrical connection between said casing, battery and lamp, and a circuit closer on the casing; of a casing supporting clip on 60 the casing and movable thereon, and a flange on said clip to maintain said clip in slightly spaced relation to the circuit closer.

In testimony whereof I affix my signature.
ANKER S. LYHNE.
